UNITED STATES PATENT OFFICE.

EDWARD ERICKSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON SHOE-BOTTOMS.

1,373,553.

Specification of Letters Patent.

Patented Apr. 5, 1921.

Application filed June 4, 1917. Serial No. 172,658.

To all whom it may concern:

Be it known that I, EDWARD ERICKSON, a citizen of the United States, residing at Beverly, in the county of Essex and State of 5 Massachusetts, have invented certain new and useful Improvements in Machines for Operating on Shoe-Bottoms; and I do hereby declare the following to be a full, clear, and exact description of the invention, such 10 as will enable others skilled in the art to which it appertains to make and use the same.

This invention relates to machines for preparing welted, unsoled shoes for the sole 15 laying operation. Such machines are known commercially as welt butting machines and, as is usual in such machines, the invention includes devices for positioning the welt ends for the butting operation, for producing 20 a bevel or scarf on each welt end, and for securing the upper to the insole at the point where the welt ends are butted.

One object of the invention is to improve 25 and simplify the mechanism for producing a scarf on the welt ends to enable it to operate at a greater speed than has heretofore been practicable, while at the same time performing the desired operations in a more efficient manner and with less expenditure of 30 power. Another object of the invention is to improve the construction and adaptability of the devices for positioning the welt ends to shoes of different sizes and styles.

A still further object of the invention is 35 to improve the construction and mode of operation of the tacker mechanism employed to secure the upper to the insole in a machine adapted to perform both the welt butting and tacking operations, providing 40 for its operation at increased speed, with greater efficiency, and with less loss of power.

The novel features of the improved tacker 45 mechanism *per se* are not claimed herein since a tracker mechanism of the kind disclosed, whether or not embodied in a machine having a welt butting mechanism, is claimed in an application Ser. No. 342,406, filed December 4, 1919, by the present inventor as a division of this application.

To the accomplishment of these objects 50 and such others as may hereinafter appear, as will be apparent to those skilled in the art, the features of the invention relate to

certain devices, combinations and arrangement of parts hereinafter described and particularly pointed out in the appended claims.

The preferred form of the invention is illustrated in the accompanying drawings, in which:

Figure 1 is a perspective of the head of the machine;

Fig. 2 is an elevation of the left hand side of the entire machine with certain portions of the frame broken away to disclose 65 certain parts of the operating mechanism;

Fig. 3 is a sectional plan on the line 3—3 of Fig. 2 of the operating mechanism for the welt butting knives;

Fig. 4 is a detail in perspective of a portion of the actuating mechanism for closing 70 the heads or swinging side frames which support the butting and tacking mechanism;

Fig. 5 is a detail in elevation with certain parts of the frame broken away of the 75 inside face of the right hand side frame;

Fig. 6 is a detail in vertical section of the lower end of the tracker mechanism;

Figs. 7, 8 and 9 are details illustrating 80 different positions of the welt butting knives and the tacker mechanisms at different times during the welt butting and tacking operations, these views being similar to that of Fig. 5;

Fig. 10 is a vertical section of the driving shaft and its actuating mechanism on the line 10—10 of Fig. 2;

Fig. 11 is an end elevation of the clutch and clutch operating mechanism at the 90 right hand side of the machine;

Fig. 12 is a detail of the clutch in vertical section, illustrating the mechanism permitting the driving shaft to be rotated by hand power;

Fig. 13 is a vertical section of the tack pot and its operating mechanism, and

Fig. 14 is an exploded view of the welt positioning device carried by the right hand side frame.

In the embodiment of the invention illustrated in the drawings and referring first to Fig. 1, the machine is provided with mechanism for positioning both welt ends for the butting operation, mechanism for butting 105 both welt ends simultaneously and mechanism for thereafter inserting tacks to secure to the insole the upper which has been lasted in

by the welt positioning operation. These various devices are mounted upon a head supported upon a column 15, the head having a forwardly projecting goose neck 17 at 5 the front of which are journaled vertical pivot rods 19 and 21 (Figs. 2, 3 and 5) on which are supported the swinging side frames 23 and 25. The side frames, as will be described later, support the welt butting 10 and tacking mechanisms with the exception of the tack delivering mechanism, comprising a tack pot 27, the supporting frame of which is secured to a bracket 29 bolted to a table 31 cast at the upper side of the goose 15 neck 17 (Figs. 1, 2 and 13).

The moving parts are driven by the rotation of a driving shaft 33 (Figs. 1, 2 and 10) which extends transversely of the head and is journaled in bearings 35 and 37 (Fig. 10) 20 at the rear of the machine provided beneath the guard plate 39 (Fig. 2). The driving shaft is normally at rest but may be connected at the will of the operator to a power shaft 41 which is continuously driven by a 25 belt running over a pulley 43 (Figs. 1 and 2).

As is usual in machines of this character, the shoe is supported and positioned vertically for the welt butting and tacking operations by means of thin plates, usually 30 termed welt supports, which are inserted in the welt crease at each side of the shoe substantially at the rear end of the inseam. Each of the swinging side frames 23 and 25 35 carries one of these welt supports. The welt support 45 for the left hand side frame is best illustrated in Fig. 1 and the welt support 47 for the right hand side frame is best illustrated in Fig. 5, while both of these 40 supports are shown in dotted lines in Fig. 3, in position beneath the welt ends. It will be understood that, as is usual in this type of machine, the welt supports are forced into the welt crease by the inward movement 45 of the swinging side frames 23 and 25 about their pivot rods 19 and 21. The consequent pressure exerted on the welt crease by the 50 welt supports causes the upper, just in advance of the heel seat tacks, to be properly lasted in.

In order to position the shoe for the proper engagement of the welt supports with the welt crease, the machine is provided with a back gage which may be adjusted longitudinally so as to locate the heels of shoes of different sizes properly for the inward movement of the welt supports. Referring to Fig. 2, the lower portion of the machine head is provided with a bracket 49 55 in which are formed horizontal ways 51 (see also dotted lines Fig. 3), within which the shank 52 of the back gage 53 can slide. Depending from the shank of the back gage is a pin 55 carrying a roll 56 which is engaged by the forked end of a lever 57, ex-

tending horizontally to the right, and loosely pivoted upon a vertical pivot pin 59 depending from a horizontal arm 61 which is a part of the bracket 49 and extends to the right beneath the side frame 25 (Fig. 1). 70 At its outer end the arm 61 supports a lock plate 63 by means of a bolt which seats in a recess in a shank pin 62 set into the arm (dotted lines Fig. 3). The lock plate 63 has a slot 65 which extends on an arc struck from the pivot pin 59 as a center. The slot is covered by a thin brass plate 64. A second lever 67, below the lever 57 (Figs. 1 and 3), is fulcrumed at its inner end on the pivot pin 59 and is provided intermediate 80 its length with a head 69 having an arcuate slot struck from the pivot pin 59 as a center. The lever 57 is clamped to the lever 67 by means of a screw bolt 71 which passes upwardly through the slot of the lever 67 and 85 is threaded into the outer, or right hand end, of the lever 57. The bolt carries, on its lower end, a wing nut 73. Beyond the head 69 the lever 67 extends farther outwardly and is provided with a handle 72 (Fig. 1) 90 which handle carries a pointer 75 overlapping the brass plate 64 on the block 63. The handle portion 72 of the lever 67 is provided with a locking device comprising a pressure piece 77 loosely pivoted at 79 on 95 the handle 72 and normally held away from the handle by a coil spring 81 interposed between the end of the pressure piece and the handle. The inner end of the pressure piece extends beneath the block 63 and is provided with two angular gripping faces 83 and 85, shown in dotted lines in Fig. 3, which are so constructed as to normally bite into the vertical sides of the rib formed at the outer edge of the block 63 by its slot 65, 100 and thus hold the back gage 53 in any desired position of adjustment. As shown best in Fig. 3, the two sides of the angle comprising each gripping face 83 and 85 are of unequal length and the apexes of the 105 angles not opposite each other because the shorter side of each angle is opposite the longer side of the other angle. By constructing the angles so that the apex on the gripping face 85 is at the same side of the 110 center line of the lever 67 as is the pressure piece 77, the skilled mechanic will recognize that pressure on 77 from the spring 81 will cause the gripping faces to bite and hold the lever 67 against forward movement, 115 while a movement of 77 toward the handle 72 will withdraw both faces from engagement with the block 63 and permit free forward movement of the lever 67. It will be observed that by locking the lever 67 against forward movement the back gage 53 is locked against rearward movement.

With the construction just described, it will be seen that by means of a movement of the lever 67 about the pivot pin 59, the 130

lever 57 is also moved and the back gage is slid in or out of its ways 51. The brass plate 64 will be provided with index marks to which the pointer 75 may be brought for 5 positioning the back gage to properly locate the welt butts on different sizes of shoes. In factories where the index marks on the plate 64 do not give a correct location of the back gage for the particular style of 10 shoe which that factory manufactures, an adjustment of the lever 57 relative to the lever 67 by means of the adjusting connections through the head 69 will compensate for such variation in style when the pointer 15 75 is brought to the index marks already provided.

The forward ends of the swinging side frames 23 and 25 are normally held apart by means of a spring 87 (Fig. 3) the ends 20 of which are attached to pins projecting from the rear ends of the side frames. In order that the two frames 23 and 25 may move together they are provided with intermeshing toothed segments 89 and 91 respectively, through which the lower ends of 25 the rods 19 and 21 extend. Treadle mechanism is provided to overcome the force of the spring 87 and bring the forward ends of the swinging side frames together into 30 position to support a shoe for the operations to be performed thereon. The operating treadle 93 (Fig. 2) is pivoted at 95 in the lower part of the column 15 and is connected by a treadle rod 97 (Figs. 2 and 4) 35 to the horizontal arm 99 of a bell crank lever pinned to a transverse rock-shaft 101 journaled in the lower part of the machine head. The vertical arm 103 of this bell crank lever is provided with a socket which receives 40 one end of a coil spring 105, the other end of which bears in a socket formed in an arm 107 which projects upwardly and has two legs 109, one at each side of the bell crank 99—103, by means of which it is 45 loosely pivoted on the rock-shaft 101. The upper end of the lever 107 is provided with a horizontal head (Fig. 4) in each end of which there is formed a socket 110 for the reception of the inner ends of struts 111 50 which extend between the head and sockets 113 (Fig. 3), for their outer ends, formed at the rear ends of the swinging side frames 23 and 25. The treadle is normally held raised by a spring 115 (Fig. 2) connecting 55 it to the column 15 so that normally the spring 105 is not under tension. When the treadle is depressed, however, the lowering of the treadle rod 97 operates through the bell crank-lever 99—103, and the spring 105, 60 to move the vertical arm 107 to the left (Fig. 2) which operates on the inner ends of the two struts 111 so as to bring the struts into a position approaching alinement, and consequently forces the rear ends of the side 65 frames apart, stretching the spring 87, as is shown in Fig. 3. This outward movement of the rear ends of the side frames causes an inward movement of their front ends and brings the welt supports into the welt crease of the shoe which has previously 70 been placed with its heel against the back gage 53 and which is held by the operative at a proper height to receive the welt supports in the welt crease.

If the forward ends of the side frames 75 were always opened to their fullest extent by the spring 87 a considerable inward movement would have to be imparted to them in order to engage shoes of the narrower widths. In order to obviate the necessity 80 of such an extensive movement a stop is provided for limiting the outward movement of the forward ends of the side frames which may be adjusted so as to provide an opening movement commensurate with the 85 width of the shoe to be operated upon. This stop is best shown in Fig. 3 and comprises a screw 117, threaded into the rear portion of the side frame 25, and provided with a head 119 adapted to engage a wear plate 90 121 carried by a portion of the segment 89 on the side frame 23. The head 119 may be adjusted toward and from the plate 121 by means of a hand wheel 123 outside of the side frame on the end of the screw 117 (Fig. 95 1). The distance of the head 119 from the wear plate 121 obviously determines the amount which the forward ends of the side frames can open under the influence of the spring 87.

It will be observed that on pressing the treadle 93 only so much pressure can be placed upon the welt crease by the welt supporting plates as is permitted by the strength of the spring 105 (Fig. 4) for, as 105 soon as the pressure equals the strength of the spring, the spring will begin to compress without further movement of the arm 107 or further straightening of the toggle formed by the struts 111. The strength of 110 the spring 105 may be varied by an adjustment of a threaded block 106 (Fig. 4) to suit the strength of the material which is being operated upon. Continued depression of the treadle will, however, continue 115 to rock the shaft 101 which movement sets in motion the driving mechanism for operating the moving parts of the machine, such parts comprising the welt butting knives, the tacker mechanisms and the tack delivering mechanism contained within the tack pot.

Referring now more particularly to Figs. 2 and 10, the power shaft 41, which extends longitudinally in the machine and is supported in a journal at the rear of the machine head, carries intermediate its length a spiral gear 125 which drives a second spiral gear 127, the hub 129 of which has a bearing upon the driving shaft 33. Connected 125 130

by a suitable driving joint to the hub 129 is a sleeve 131, which forms the bearing for a Horton clutch. This clutch, as is usual, is provided with a clutch ring 133 formed as 5 a part of the bearing sleeve 131, a cam ring 135 which is keyed to the driving shaft 33, a roll carrier 137 with its rolls 139, interposed between the clutch ring and cam ring, and an operating spring 141 (dotted lines 10 Fig. 11). It is thus seen that the spiral gear hub 129 and clutch ring hub 131 form a hollow shaft which is continuously driven from the power shaft. Interposed between the driving shaft bearing 37 and the spiral 15 gear 127 is a suitable thrust bearing 143. Intermediate the two bearings 35 and 37 of the driving shaft 33 and located on the median line of the two swinging side arms is a crank 145 (Figs. 2 and 10), the rotation 20 of which, through connections to be described later, operates the welt butting knives and the tacker mechanisms. At the left hand end of the shaft 33 outside the machine frame, there is secured a disk 147 25 which carries a wrist pin 149 to which is connected, by the yoke shown in Fig. 2, a pitman 151 which through its reciprocations operates the mechanism for delivering tacks to the tack tubes for delivery to the 30 tacker nozzles.

30 TACKER NOZZLES.

On the right hand end of the rock shaft 101 is an arm 153 (Figs. 1 and 11) which carries an adjustable tappet 155. When the shaft 101 is rocked sufficiently by pressure on the treadle 93, the tappet 155 engages the forwardly projecting arm 157 of a three-armed lever pivoted loosely upon a horizontal stud 159 (Figs. 10 and 11) carried by the machine frame, and the movement thus imparted to this lever causes the Horton clutch to become engaged, to rotate the driving shaft 33 through a single revolution, by means now to be described. The rearwardly projecting arm 161 of the three-armed lever has pivoted thereto, by its lower end, an upwardly projecting rod 163 which passes through a yoke formed at the forward end of a horizontally disposed lever 165 pivoted upon a second stud 167 threaded into the machine frame. The lever 165 carries, at the rear side of the stud 167, an arm 169 which supports the usual yielding buffer 171 adapted to be engaged by the usual stop shoulder on the Horton clutch at the time the clutch is disconnected. The lever 165 also has secured thereto a tooth 173 which is engaged by a shoulder 175 cut in the rear edge of the vertical rod 163. A spring 177 connected at its forward end to the rod 163 and at its rear end to the buffer supporting arm 169 normally holds the buffer in position for stopping the clutch and draws the rod 163 rearwardly into engagement with the tooth 173. A second spring 179 connected at its forward end

to the third arm 181 of the three-armed lever hereinbefore referred to, and by its rear end to a pin 183 (Fig. 10) carried by the machine frame normally maintains the tappet engaging arm 157 of the lever in raised position and holds the shoulder 175 below the tooth 173. 70

The driving shaft 33 also has secured thereto a brake wheel 185 which, at the time the clutch is disconnected, is engaged by a brake shoe 187 which, as shown in Fig. 11, partially surrounds the brake wheel. The brake shoe is mounted upon an eccentric bearing 189 which in turn is carried upon a reduced portion 191 of the hub of the lever arm 165 (Fig. 10). The eccentric bearing is formed as a split ring and is secured to the reduced hub 191 by means of a clamping bolt 193 (Fig. 11). A cap plate 195 holds all of these parts in place on the stud 167. It is readily seen that with this construction whenever the buffer arm 169 is thrown inward to disconnect the Horton clutch the eccentric bearing 189 is rotated and moves the brake shoe 187 into engagement with the brake wheel 185, and vice versa a movement of the buffer arm 169 to the right, in Fig. 11, to permit the clutch to operate will, by a reverse rotation of the eccentric mounting 189, withdraw the brake shoe from the brake wheel. By loosening the cap plate 195 and the bolt 193 the eccentric bearing may be adjusted angularly as may be necessary to increase its throw whenever it becomes desirable to do this by reason of wear of the parts of the brake.

The operation of these parts will be understood best from Fig. 11; it being apparent that when the tappet 155 descends the three-armed lever is rotated on its pivot in a direction to raise the rod 163, and consequently through engagement of the shoulder 175 with the tooth 173 rock the lever 165 in a direction to withdraw the buffer 171 from its engagement with the stop of the Horton clutch. Simultaneously with this movement the brake is released and the spring 141 of the Horton clutch moves the roll carrier in a direction to cause the rolls to bind and drive the shaft 33. 115

It is not desired, however, that it be necessary for the operative to maintain his foot on the treadle while the driving shaft is rotating and the welt butting and tacking mechanisms are being operated. Some means must be provided, therefore, for locking the swinging side frames in the position to which they have been moved by the depression of the treadle. Such a locking mechanism is illustrated in Fig. 2 and comprises a vertical arm 196 secured to the rock-shaft 101 having pivoted to its upper end the forward end of a rectangular rod 197, the rear end of which extends through a rectangular opening in an arm 199, depending 120

from, and pivoted freely on, a horizontal stud 201 carried by the machine frame. The free end of the arm 199 is normally pulled forward by a spring 203 connected between the arm and the frame. When the machine is in a position of rest a pin 205 on the disk 147 at the end of the driving shaft is in engagement with an upwardly projecting ear 207 carried by the arm 199 and maintains this arm in such position that the rod 197 can slide freely through the rectangular opening in the arm. As soon as the driving shaft 33 begins to rotate, however, the pin 205 is removed from its engagement with the ear 207 and this permits the spring 203 to rock the arm 199 to an angular position with relation to the rod 197 whereby the corners of the opening in the arm above and below the rod will bind on the rod and act as a lock to prevent the rock-shaft 101 from rotating under the influence of the extended treadle spring 115.

In order to hold the rotation of the driving shaft to a single revolution, the roll carrier 137 of the Horton clutch is provided with a radial pin 209 (dotted lines Fig. 11) which, on the clockwise rotation of the driving shaft 33, engages the upper end of the rod 163 pushing this rod forward about its pivot and withdrawing the shoulder 175 from beneath the tooth 173. The spring 177 immediately acts to pull the clutch buffer 171 into position to be engaged by the clutch stop at the same time applying the brake by reason of the angular movement imparted, by the movement of the lever 165, to the eccentric brake bearing 189. Immediately after this operation the pin 205 on the disk 147 (Fig. 2) engages the ear 207 of the lock arm 199 and turns this arm to a position normal to the rod 197 so as to release the clutch operating tappet 155 to the influence of the spring 105 and also the side frames to the influence of the treadle spring 115. Consequently, the tappet 155 is withdrawn from its engagement with the three-armed lever, the spring 179 is enabled to return the clutch operating parts to the position shown in Fig. 11, and the spring 87 which connects the rear ends of the side frames operates to open the frames about their pivot rods 19 and 21 and thus release the shoe from its engagement by the welt supporting plates 45 and 47. In the meantime, during the single revolution of the driving shaft, the two welt ends have been butted and two tacks, one at each side of the shoe, have been driven.

The mechanism for supplying tacks to the usual tack nozzles beneath the tack drivers will now be described. Referring more particularly to Fig. 13, the tack pot 27 comprises a casting 211, secured to the bracket 29, which sustains the double raceway 213, the tack picker 215, the tack picker

block 217 through which tacks are delivered by the picker to the tack tubes 219, and the tack picker slide 221 which is reciprocated through suitable connections, presently to be described, to operate the tack picker. The casting 211 projects within and forms a bearing for the forward open end of the oscillating, cylindrical tack pot 27 proper, and a tack receiving pan 223 is so located on the end of the raceways 213 that oscillations of the tack pot 27 will cause its shelf 225 to pick up and drop tacks upon the pan in the usual manner. The tack pot 27 is oscillated by the reciprocations of the pitman 151 (Fig. 2) driven by the wrist pin 149. The upper end of the pitman is connected, by the yoke shown in Fig. 2, to the horizontal arm 227 of a bell crank lever secured to a rock-shaft 229 (Fig. 13) which is journaled at its ends in the bracket 29 and the casting 211. The vertical arm 231 of this bell crank is provided with a toothed segment which meshes with a pinion 233 secured to the rear end of a second rock-shaft 235 journaled in the bracket 29 which carries the tack pot 27 at its forward end. With this construction the rotation of the driving shaft 33 causes an oscillation of the tack pot and a consequent delivery of tacks to the raceways 213. 95

The tack picker 215, which is a plate having oblique tack picking slots of the usual construction adapted to simultaneously engage and separate one tack from each raceway, is reciprocated by connections with the two ends of the tack picker slide 221 comprising depending arms 237 (Figs. 1 and 13). The slide 221 is T-shaped in cross-section and slides in a way formed below the raceways 213. The lower face of the slide 221 is provided with teeth which mesh with a toothed segment 239 secured to the forward end of the rock shaft 229. Thus, at each oscillation of the tack pot 27 the picker plate 215 is advanced to separate two tacks and then withdrawn to its inactive position in which position it retains the remaining tacks in the raceway as is usual. The picker block 217 may be removed so as to obtain access to the raceways by lifting the hook 241 (Figs. 1 and 13) from the pin 243, which is secured to the lower end of the raceway and projects outwardly, centrally through the picker block, and then sliding the block off the pin. The removable block 217 has secured to its upper side a double slotted plate 218, forming an extension of the raceway and lying just above the picker plate 215, which plate 218 is somewhat longer than the block 217 to provide a proper jointure with the raceway, all as shown in Fig. 13. The lower end of the cover plate of the raceway is constructed in the form of a spring-pressed gate 245, as shown in Fig. 13, which may be lifted for purposes of inspection. 130

The raceway is also provided with a tack clearing mechanism, shown best in Fig. 13, journaled in bearings 246. At each side of the casting 211 are pins 247 eccentrically mounted at each end of a rotary shaft 249 on which shaft are secured the clearer blades 251. Each pin 247 has mounted thereon a pinion 253 adapted to be engaged by vertical racks 255, moving in guides 256 at each side of the casting 211, (see also Figs. 1 and 2) which are connected at their lower ends by links 257 to the arms of a lever 259 which project laterally from the hub of the segment 239 secured to the rock shaft 229. Each of the bearings 246 for the pins 247 contains a Horton clutch and by means of these clutches the alternate reciprocations of the racks 255 from the oscillations of the lever 259 are permitted to drive the shaft 249 continuously in one direction. The shaft 249 is provided at one end with an ear 261 (Fig. 13), which has a pin 263 projecting outwardly into a guide slot cut in the inner wall of the casting 211 which constrains the movement of the clearers 251 to the usual oscillation lengthwise of the raceways. One of the pins 247 is extended and carries a hand wheel 248 by means of which the shaft 249 may be rotated while the machine is idle.

The tack pot is provided with a spring-pressed door 265 in its rear face (Fig. 13) through which it may be emptied of its tacks into the shelf 267. The casting 211 is also provided with a door 269 at its top through which inspection may be had of the parts inside, and with a waste tack receiving shelf 271.

The shoe having been positioned by a depression of the treadle, the driving shaft having been connected to the power shaft by the actuation of the driving shaft clutch, and a tack having, on the previous operation, been delivered to each of the tack tubes 219, the welt is then butted and subsequently tacked by the instrumentalities now to be described.

Referring first to Fig. 2, the crank 145 of the driving shaft 33 is connected by a pitman 272 to a piston 275 which is guided within a cylindrical way 277 cast centrally in the lower part of the goose neck 17. Projecting from the forward end of the piston 275 is a connecting rod 279 (Fig. 2) provided with an H-shaped head 281 (see dotted lines Fig. 3) which lies horizontally with the legs of the H pointing outwardly toward the side frames 23 and 25. The slots 283 and 285 formed between the legs of the H carry cubical slide blocks 287 and 289 which are drilled vertically for the reception therethrough of vertical pins carried by the welt butting knife operating slides 291 and 293. With this construction a rotation of the

crank 145 to withdraw the piston 275 within its guideway causes the slides 291 and 293 to withdraw and operate the welt butting and tacking mechanism.

As the side frames 23 and 25 which form the guides for the slides 291 and 293 are usually at an angle to the line of movement of the piston 275, the slots 283 and 285 in the head 281 provide for an outward movement of the connecting blocks 287 and 289 as the slides are withdrawn. Since the mechanism carried by each of the side frames is identical, it will be sufficient to describe the mechanism at one side only. The mechanism upon the side frame 25 at the right hand side of the machine will be used for this purpose.

Referring more particularly to Fig. 5, which illustrates the various mechanisms on the side frame 25 in a position of rest, the welt butting knife slide 293 is connected to the block 289 by a pin 295 which extends between two inwardly projecting ears at the rear end of the slide. The slide rests upon a flat track, or way, 297 formed at the lower end of the side frame 25. The slide is T-shaped in cross-section (Fig. 14) and is guided during its rearward movement by the side walls of the swinging frame which are recessed to overlap its T-head (see broken away parts of Fig. 2). The upper part of the slide 293 is channel shaped (Fig. 14) for the greater portion of its length and its side walls are cut and drilled at two separate points for the reception of the lower cylindrical ends of two links 299. The upper ends of these links are received in similar openings formed in a channel shaped welt butting knife carrier 301 (Fig. 5), but the link openings in the carrier are farther apart than those in the slide, as shown in Figs. 7 to 9. This mounting of the knife carrier permits it to be rocked back and forth relative to the knife slide to lower and raise the welt butting knife relative to the shoe. The movement in a rearward direction is limited by the end of the carrier abutting against a shoulder 303 (Fig. 9) formed on the slide and a movement in a forward direction is limited by the engagement of an adjustable stop screw 305 (see Fig. 7) with the surface of the nose 307 of the slide. The welt butting knife 309 which extends inward laterally from the carrier (see Fig. 3) is clamped to the end of the carrier in a dove-tail slot by means of a block 311 (Fig. 5) having a pin extending forwardly through a downwardly projecting portion of the end of the carrier and secured in place by a nut. Just in front of the knife is a welt presser 313 (Fig. 3) which is provided with a shank 315 extending upwardly through a guideway formed for its reception in the carrier 301 (Fig.

5). This welt presser is yieldingly held in engagement with the welt by means of a grasshopper spring 317 secured at one end to the upper side of the carrier and having 5 its other extending over a pin projecting from the shank of the presser. As shown best in Fig. 3, the presser has a beveled and toothed forward edge by which it may engage beneath the heads of and pull any 10 tacks which may have inadvertently been left in the shoe in the path of the welt butting knife.

The welt supports 45 and 47 hereinbefore referred to are supported adjustably, 15 to accommodate varying styles of shoes, at the forward ends of the swinging side frames 23 and 25 just below the nose 307 of the welt butting knife slide 293. The mounting of these supporting plates is best 20 shown in Fig. 14 which illustrates the welt support 47 for the side frame 25. The welt support is provided with a curved, dove-tail projection 319 which fits into a curved dove-tail guideway 321 formed in the inner 25 face of a welt plate holder 323. The holder 323 is provided with a horizontal pin 325 which is received in a bore made for its reception in an adjustable welt plate block 327 which in turn has a horizontal pin 329 30 received in a bore 331 extending longitudinally in the front end of the side frame. The block 327, and consequently the welt supporting plate 47, may be adjusted longitudinally of the shoe by turning the collared adjusting screw 333 (see Figs. 5 and 35 14) which fits in a slot in an ear 334 depending from the block 327. After having been adjusted the pin 329 is held from 40 movement by the locking pin 335. The welt supporting plate 47 may be adjusted transversely of the shoe, if desired, by loosening the locking pin 337, which binds on the pin 325, and then moving the holder 323 across 45 its supporting shelf 338. The welt plate holder has formed integral therewith a guard plate 339 which extends over the heel seat of the shoe, as best shown in Fig. 3, and over which the welt butting knife 309 travels after the welt has been severed. In order 50 to produce a scarf or beveled end on the end of the welt, the surface of the supporting plate 47 is set at an angle to the surface of the guard plate 339 (see Fig. 5) as is usual in machines of this type. This 55 angular position of the welt supporting plate may be altered to obtain any length of scarf that may be required by loosening the set screw 341 and shifting the welt supporting plate angularly in its guideway 321, 60 it being understood that the sides of this guideway are formed on arcs of circles having the joint between the welt supporting plate and the guard plate as a center. Since the welt butting knife, during its cut-

ting stroke, travels in the plane of the surface of the guard plate 339, it will be obvious that a welt end which lies in contact with the welt supporting plate 47 will be severed on a plane passing angularly from one surface of the welt to the other, the inclination of the cut to the surface of the welt being determined by the inclination of the welt supporting plate relative to the guard plate.

Since the movement of the welt butting 75 knife slides 291 and 293 also actuates the tacker mechanism, a description of the operation of the welt butting mechanism will be deferred until the tacker mechanism has been described. Referring still to Fig. 5 for 80 a disclosure of the tacker mechanisms, the forward edge of each swinging side frame is grooved vertically to form a rectangular way 343 which is closed by a face plate 345 (see also Figs. 1 and 2). Within this way 85 is seated, for vertical sliding movement, the driver slide 347. This slide 347 is bored longitudinally for the greater part of its length for reception of the cylindrical driver bar 349. At its lower end the slide 90 347 is provided with a reduced bore through which the tack driver 351 extends (Fig. 6). The tack driver is secured to the lower end of the driver bar by a nipple 353 in the usual manner. Also the lower end of the 95 driver slide has secured thereto, by a second nipple 355, a suitable tack nozzle 357. At its upper end the driver bar is provided with a head 359 (Fig. 5) the rear end of which is bifurcated and embraces the two sides of a 100 vertical track 361 formed on the side frame. A roll is carried by the head 359 which engages the track 361 and guides the bar in its movement through the driver slide. The extreme upper end of the driver bar carries 105 a conical cap 363 which is engaged by a socket on one end of the coiled driving spring 365. The other end of the driving spring is connected to a block 367 having a pin secured in a bearing 369 (see Fig. 2) at 110 the rear side of the driver slide. Pivoted by its lower end, at 371, in a vertical slot formed for its reception at the upper end of the face plate 345 is a lever 373 (dotted lines Fig. 5) carrying at its upper end a 115 roll 375 which is normally held in the path of movement of the driver bar head 359 by means of a spring-pressed pin 377. The inward movement of the lever 373 is limited by an ear on the lever engaging a stop pin 120 381 mounted in the face plate. The driver head 359 is provided with a beveled surface 383 so located that on the upward movement of the driver bar the roll 375 is cammed to one side until the head has 125 reached a position above the roll when the roll snaps back beneath the head and supports the driver bar against downward

movement. The lever 373 is also provided with a cam piece 385 which projects into the path of and is adapted to be engaged by a cam piece 387, formed at the upper end of 5 the driver bar slide, when said slide descends. The purpose of this action will presently be described. The driver bar slide is provided at its rear side with teeth 389 and forms, in effect, a rack which is engaged 10 by the teeth of a segment 391 carried by a shaft 393 journaled in the side frame. The segment is provided with a downwardly projecting part which forms a crank arm and is connected at its lower extremity by 15 a link 395, to an arm 397 extending upwardly from and integral with, the welt butting knife carrier 301 (see Fig. 5).

As shown best in Fig. 1 all the moving parts just described are held within the 20 swinging side frame 25 by a cover plate 26 suitably bolted on, and a similar cover plate 24 is provided for the side frame 23 (see Fig. 2).

Referring now particularly to Figs. 7, 8 25 and 9, and remembering that the moving parts just prior to the welt butting operation are in the relative positions shown in Fig. 5, when the driving shaft 33 commences to rotate the piston 275 and its H-shaped head 281 are drawn backwardly, or 30 away from the operative, which causes the welt butting knife slides 291 and 293 to be drawn rearwardly. Describing now the operation of one of the knives only, as the slide 35 293 is withdrawn on its track 297, the resistance offered by the tacker mechanism causes the links 299 to pivot about their lower ends and tilt the welt butting knife carrier 301 forward until its stop screw 305 40 engages the nose 307, as shown in Fig. 7. This brings the welt presser into engagement with the welt and places the knife in the plane of the surface of the guard 339, this position being determined by a proper 45 adjustment of the screw 305. Further rearward movement of the piston 275 now draws both the slide and the carrier rearwardly together causing the knife to cut through and bevel the welt end. As the welt butting 50 knife carrier 301 moves rearwardly it draws with it the link 395 and, by turning the segment 391, draws the driver bar slide 347 downwardly relative to the driver bar. The tack which has been resting in a tackway 55 348 formed for its reception in the inner side of the driver bar slide just above the nozzle 357, as shown in Fig. 6, drops into the nozzle when the driver bar slide has been drawn down sufficiently for the tackway to come 60 below the lower end of the driver. The tack is now in position to be driven whenever the driver is permitted to descend. The downward movement of the driver bar slide acts to continually place tension upon the driver 65 spring 365, since the driver bar itself is held

from downward movement by reason of its head 359 being above the roll 375 on the latch lever 373. Just as the nozzle 357 reaches the shoe, as shown in Fig. 8, the cam 387 on the driver bar slide engages the cam 70 385 on the latch lever and pushes the latch lever to the right in Fig. 5, so as to withdraw the roll 375 from beneath the head 359 of the driver bar. This immediately releases the driver bar to the action of the 75 now fully tensioned driving spring 365 and the tack is driven into the shoe, the parts at this time being as shown in Fig. 8. The crank 145 has now passed through a half revolution and the welt butting knife slide 80 293 is again moved forward, first relatively to the carrier 301 which causes the links 299 to tilt backward until the rear end of the carrier engages the shoulder 303 (see Fig. 9) thus raising the welt butting knife from 85 the shoe. The forward motion of the carrier 301 actuates the link 395 to reversely rotate the segment 391 and again raise the driver bar slide 347. Since the head of the 90 driver bar rests at this time upon the upper end of the driver bar slide, the driver and its driving spring are both raised together until the latch 373 is tilted outwardly by engagement of the cam surface 383 with the roll 375 and the head 359 eventually rests 95 upon the roll 375.

A friction plug 399 is seated in the face plate 345 and spring pressed, as shown in Fig. 5, against the forward side of the driver bar slide 347. This plug offers sufficient resistance to prevent movement of the segment 391 during the first part of the movement of the crank 145 to lower the cutter 309, and provides means for insuring that the cutter carrier 301 is moved toward and 100 from the welt rest about its pivotal connection with the cutter slide 293. The plug performs a like function to restrain the carrier from moving relatively to the slide at the start of the return movement, thus raising 105 the knife from the welt before the carrier is advanced by the slide to its forward position ready for another cutting stroke.

Each driver bar slide is also provided with a longitudinal groove 350 in its inner 110 face, shown best in Fig. 6, which forms an upward extension of the tackway 348, the function of which is to receive any extra tacks which may have inadvertently been discharged, which may lie partially in the tack tube and tackway, and thus prevent jamming when the tacker slide is moved downward.

The pivot 371 of the latch lever 373 is integral with the lever and turns in a bore 115 made for its reception at the inner side of the face plate 345. The recess within the face plate is of such dimensions that when the lever is turned to a horizontal position the pivot may be slipped sidewise out of 120

the bore and the lever removed from the face plate.

It is sometimes desirable to turn the driving shaft 33 over by hand and to enable this 5 to be done means is provided for locking the roll carrier 137 of the Horton clutch to the - brake wheel 185 (see Fig. 12). The inner face of the brake wheel is recessed for the reception of the head 401 of the plunger 403, 10 a spring 405 being inserted behind the head of the plunger which normally tends to force the plunger head into a recess 407 made for its reception in the outer face of the roll carrier 137. The plunger head is normally 15 maintained within the recess 406 by means of a transverse pin 409 extending through the plunger at the outer side of the brake wheel and resting in a groove in a shelf 411 arranged for this purpose. However, by 20 pulling outwardly on the plunger handle 413, the pin 409 may be turned ninety degrees and its ends dropped into a deeper, second groove 415 which permits sufficient inward movement to the plunger, under the influence 25 of the spring 405, to project the plunger head 401 into the recess 407 in the roll carrier. This locks the roll carrier to the shaft 33 and permits the shaft to be turned, by hand power, by means of a suitable 30 wrench which may be applied to the shoulders 417 (Fig. 11) formed on the outer face of the brake wheel.

The simplicity of operation of the machine will at once be apparent to those skilled 35 in the art. No rotary cams are used, as power for driving the moving parts of both the welt butting and tacking mechanisms is derived from a single crank motion, and a second crank motion actuates the tack sup- 40 plying mechanism. The efficiency of the machine is thereby enhanced and the speed of operation permitted to be increased over machines heretofore developed for the purposes described. The tacker operating 45 mechanism is such that when the machine is at rest, with the drivers held withdrawn from the shoe, the driving spring is not under tension thus making it easy to dismantle this mechanism whenever desired. 50 All necessary adjustments for properly positioning any size or style of shoe are provided, as well as provision for insuring that too great pressure will not be applied to the welt crease of any shoe that may be presented to the machine. The side frames are 55 so constructed as to provide for carrying the drivers at an inclination to the shoe bottom as is usual, whereby the tacks are uniformly clenched on the iron heel plate 60 of the last. Throughout, the mechanism is simple, easily assembled and sturdy.

The nature and scope of the present invention having been indicated, and the preferred embodiment of the invention having 65 been specifically described,

What is claimed as new, is:—

1. A machine for operating on welted, unsoled shoes, having, in combination, connected welt butting and upper tacking mechanisms, and a single actuator connected 70 to the welt butting mechanism for operating both of said mechanisms, one from the other.

2. A machine for operating on welted, unsoled shoes, having, in combination, welt butting and upper tacking mechanisms, a 75 single actuator for operating both of said mechanisms, and connections between said mechanisms permitting a delayed action of the tacking mechanism.

3. A machine for operating on welted, unsoled shoes, having, in combination, welt butting and upper tacking mechanisms, including a cutter carrier and a tacker nozzle both movable toward and from the welt, connections between said carrier and nozzle, a 85 single actuator for said parts, and means providing for the movement of said parts in sequence.

4. A machine for operating on welted, unsoled shoes, having, in combination, connected welt butting and upper tacking mechanisms, including a cutter and a tack driver and driver spring, and a single actuator for moving the cutter to sever the welt and thereafter release the driver to the ac- 95 tion of its spring.

5. A machine for operating on welted, unsoled shoes, having, in combination, welt butting mechanism including a cutter, upper tacking mechanism including a tack driver, 100 an actuator for the cutter, and connections between said mechanisms whereby the movement of the welt butting mechanism operates the tack driver.

6. A machine for operating on welted, unsoled shoes, having, in combination, a welt butting cutter, means to operate said cutter, tacking mechanism including a tack driver spring, and connections providing for tensioning the spring from the movement of 110 the cutter operating mechanism.

7. A machine for operating on welted, unsoled shoes, having, in combination, welt butting and upper tacking mechanisms including a welt cutter and a tacker nozzle both 115 normally withdrawn to a position above the insole of the shoe, and a single actuator for advancing both of said parts into position for operating on the shoe.

8. A machine for operating on welted, unsoled shoes, having, in combination, a welt butting cutter slide, a cutter carrier sustained on said slide having a cutter, a tack driver slide having tack driving mechanism associated therewith normally withdrawn 125 from the shoe, connections between said cutter carrier and driver slide constructed to advance the driver slide when the cutter slide is actuated, and means for actuating the cutter slide. 130

9. A machine for operating on welted, unsoled shoes, having, in combination, a welt cutter movable toward and from the welt and longitudinally thereof, a tacker mechanism movable toward and from the shoe, and common means for causing the cutter to approach the welt and then travel longitudinally and for causing the tacker mechanism to approach the shoe and drive a tack at the completion of the cutter movements. 5
10. A welt butting machine, having, in combination, a cutter slide; a cutter carrier, having a cutter, mounted for rocking movement on said slide to move the cutter toward and from the welt; means for actuating the slide; and means for initially restraining the carrier from moving with the slide whereby the carrier is rocked to carry the cutter toward the welt. 15
11. A welt butting machine, having, in combination, a cutter slide; means for reciprocating said slide longitudinally; a cutter carrier, having a cutter, pivotally mounted on said slide; and means for restraining the carrier from moving with the slide at the start of each stroke of the slide whereby the carrier is rocked about its pivotal connection to move the cutter toward and from the welt. 25
12. A welt butting machine, having, in combination, a cutter slide, a cutter carrier having a cutter, and a link connection between said parts constructed and arranged to permit the carrier to rock on the slide. 30
13. A welt butting machine, having, in combination, a cutter slide, and a cutter carrier having a cutter, said parts being joined together by two links having their connections to the carrier spaced farther apart than their connections to the slide. 35
14. A welt butting machine, having, in combination, a cutter slide, a cutter carrier having a cutter mounted on said slide, said carrier being held in spaced relation to the slide but relatively movable thereto, and means to limit the movement of the cutter relatively to the slide. 45
15. A welt butting machine, having, in combination, a cutter slide; a cutter carrier, having a cutter, above the slide; a link joining said parts permitting the carrier to rock toward and from the slide; and a stop to limit the movement of the carrier toward the slide and determine the operative position of the cutter. 50
16. A welt butting machine, having, in combination, a cutter slide; a cutter carrier, having a cutter, above the slide; a link joining said parts permitting the carrier to rock toward and from the slide; and means for limiting the rocking movement of the carrier in both directions. 60
17. A welt butting machine, having, in combination, a cutter slide; a cutter carrier connected thereto near its forward end by a link between said parts; a similar link connecting the rear end of the carrier to the slide; a cutter supported by the carrier, means to move the slide; and means to restrain the carrier from movement with the slide for a time whereby the carrier first rocks on the links and then moves with the slide. 70
18. A welt butting machine, having, in combination, a cutter slide; a cutter carrier, having a cutter at its forward end, above the slide; a link connecting said parts near their forward ends; a similar link arranged at an angle to the first link connecting said parts near the their rear ends; means to reciprocate the slide; and means to restrain the carrier from movement with the slide for a time whereby the links are rocked and the cutter is moved down or up according to the direction of movement of the slide. 75
19. A welt butting machine, having, in combination, a cutter carrier, a welt butting cutter sustained thereby, a tack pulling tool in advance of the cutter having an operating portion to engage beneath the head of a tack, and means for actuating the carrier. 80
20. A welt butting machine, having, in combination, a cutter carrier, a welt butting cutter sustained thereby, and a combined welt presser and tack puller sustained on the carrier in advance of the cutter. 95
21. A welt butting machine, having, in combination, a support for the welt, a welt butting cutter arranged to travel in the plane of said support, a yieldingly mounted tack puller in advance of the cutter having an operating portion to engage beneath the head of a tack, and means for operating said tools. 100
22. A welt butting machine, having, in combination, a pair of welt butting cutters, a slide for each cutter movable longitudinally of the welt, a central sliding head connected to both of said slides, and a crank for reciprocating said head. 105
23. A welt butting machine, having, in combination, a pair of swinging heads, a slide for each head movable in a slide way therein, a welt butting cutter mounted on each slide, a central head to which said slides are pivotally connected movable in a slide way in the machine frame, and a crank for reciprocating said head. 115
24. A machine for operating on shoe bottoms, having, in combination, a pair of swinging heads normally held open, a welt support carried at the inner side of each head, and a stop carried by one head adapted to engage the other and predetermine the opening between said welt supports. 120
25. A machine for operating on shoe bottoms, having, in combination, a pair of articulately connected swinging heads carried on vertical pivot rods; a welt support on each head at the forward end thereof; 125

yielding means for holding said heads swung open; and an adjustable stop positioned for engagement by one of the heads to limit the distance the heads swing under 5 the influence of said yielding means.

26. A machine for operating on shoe bottoms, having, in combination, a pair of articulately connected swinging heads each carried on a vertical pivot rod intermediate its 10 front and rear end, a welt support on each head at its front end, means for normally holding the rear ends together, and a toggle mechanism for forcing the rear ends apart and causing an approach movement of the 15 welt supports.

27. A machine for operating on shoe bottoms, having, in combination, a pair of articulately connected swinging heads each carried on a vertical pivot rod intermediate 20 its front and rear end, a welt support on each head at its front end, means for normally holding the rear ends together, a toggle mechanism for forcing the rear ends apart and causing an approach movement 25 of the welt supports, and means for operating said toggle mechanism through an interposed spring.

28. A machine for operating on shoe bottoms, having, in combination, a pair of 30 swinging heads normally held open, a welt support carried by each head, means under control of the operative to swing said heads to cause the welt supports to engage the shoe, and means operated by the machine 35 for locking said heads in the position to which they are swung.

29. A machine for operating on shoe bottoms, having, in combination, a pair of 40 swinging heads normally held open, a welt support carried by each head, means under control of the operative to swing said heads to cause the welt supports to engage the shoe, and an automatically operating device 45 for locking the heads from opening again actuated by said means to swing the heads.

30. In a machine for operating upon shoe bottoms, a welt support mounted for adjustment, longitudinally and transversely of the welt, and angularly relative to the 50 face of the welt, and means for holding said support in adjusted position.

31. In a machine for operating upon shoe bottoms, a welt support mounted for adjustment longitudinally of the welt and 55 angularly relative to the face of the welt, and means for holding said support in adjusted position.

32. In a machine for operating upon shoe bottoms, a welt support provided with a heel 60 seat guard mounted for adjustment transversely with the guard and angularly relative to the guard.

33. In a machine for operating upon shoe bottoms, a welt support provided with a 65 heel seat guard and adjustable angularly

about its juncture with the guard as a center.

34. A welt butting machine, having, in combination, welt butting mechanism, operating mechanism therefor including a crank 70 on a normally idle crank shaft, a continuously driven sleeve on the crank shaft, a power shaft at an angle to the crank shaft provided with means for driving said sleeve, and means under the control of the operative for connecting the sleeve and shaft. 75

35. A welt butting machine, having, in combination, a pair of heads carrying welt butting cutters, means to reciprocate the cutters longitudinally of the welt, including a 80 crank motion normally inactive, means to move the heads to bring the cutters into operating position, and mechanism controlled by said last named means to actuate the crank motion. 85

36. A welt butting machine, having, in combination, a pair of swinging heads mounted on pivots in the frame at the rear of the shoe, said heads carrying welt butting cutters at their forward ends, cutter operating mechanism, and common means to swing the heads to bring the cutters into operating position and actuate the cutter operating mechanism. 90

37. A machine for operating on welted, 95 unsoled shoes, having, in combination, a pair of swinging heads normally held open, welt butting and upper tacking mechanism carried by each head, means under control of the operative to swing said heads inward 100 to bring said mechanisms over the shoe, means for locking the heads in their inward position, means for operating said mechanisms, and means controlled by said last named means to release the locking mechanism 105 after the welt has been butted and the upper tacked.

38. A machine for operating on welted, unsoled shoes, having, in combination, welt butting mechanism including a cutter normally removed from the shoe, a driving shaft, a clutch for operating the driving shaft, connections from the driving shaft for operating said mechanism, means for positioning said cutter above the welt preparatory to operating on the welt, and means for concurrently connecting the clutch to the driving shaft. 110

39. A machine for operating on welted, unsoled shoes, having, in combination, welt 115 butting mechanism including a cutter normally removed from the shoe, a driving shaft, a clutch for operating the driving shaft, connections from the driving shaft for operating said mechanism, and a single 120 means for positioning said cutter above the welt preparatory to operating on the welt and actuating the driving shaft.

40. A machine for operating on welted, unsoled shoes, having, in combination, welt 125

butting mechanism normally removed from the shoe, a driving shaft, a clutch for operating the driving shaft, connections from the driving shaft for operating said mechanism, a single means for positioning said mechanism for operating on the welt and actuating the driving shaft, and means controlled by the rotation of the driving shaft for locking said mechanism in operating position and after the completion of the welt butting operation releasing the lock and disconnecting the shaft from the clutch.

41. A machine for operating on welted, unsoled shoes, having, in combination, a welt butting cutter slide, a cutter carrier sustained on said slide having a cutter normally withdrawn from the welt, a tack driver slide having tack driving mechanism associated therewith normally withdrawn from the shoe, connections between said cutter carrier and driver slide for operating the latter from the former, and means for rendering said connections ineffective to move the tack driving mechanism toward the shoe until the cutter carrier has placed the cutter in contact with the welt.

42. A machine for operating on welted, unsoled shoes, having, in combination, a welt cutter movable toward and from the welt, a tacker mechanism movable toward and from the shoe, connections therebetween for operating one from the other, and means for initially restraining the tacker mechanism from moving until the welt cutter has completed its movement.

43. A welt butting machine having, in combination, a pair of welt butting cutters, a pair of welt supports for pressing in the welt crease at each side of the shoe and positioning the welt for the operation of said

cutters, means under control of the operative to actuate said welt supports, and means operated by the machine for locking them against movement while the cutters are operated.

44. A welt butting machine having, in combination, a pair of welt butting cutters, a pair of welt supports for pressing in the welt crease at each side of the shoe and positioning the welt for the operation of said cutters, means under control of the operative to actuate said welt supports, and means operated by the machine for locking said supports against movement prior to the operation of said cutters and for freeing them after the completion of said cutter operation.

45. A welt butting machine having, in combination, a pair of welt butting cutters, a pair of welt supports for pressing in the welt crease at each side of the shoe and positioning the welt for the operation of said cutters, means under control of the operative to actuate said welt supports, automatic means to operate said cutters, a normally inactive locking mechanism adapted when active to hold said supports from movement, and a device controlled by said automatic means to cause said locking mechanism to become active and again be rendered inactive before and after the operation of said cutters respectively.

46. A welt butting machine having, in combination, a cutter carrier, a welt butting cutter sustained thereby, and a tool sustained on the carrier in advance of the cutter having a smooth face to press the welt and a serrated forward edge to engage and pull tacks.

EDWARD ERICKSON.

It is hereby certified that in Letters Patent No. 1,373,553, granted April 5, 1921, upon the application of Edward Erickson, of Beverly, Massachusetts, for an improvement in "Machines for Operating on Shoe-Bottoms," an error appears in the printed specification requiring correction as follows: Page 1, line 79, for the word "tracker" read *tacker*; and that the said Letters Patent should be read with this correction therein that the same may conform to the record of the case in the Patent Office.

Signed and sealed this 7th day of June, A. D., 1921.

[SEAL.]

KARL FENNING,
Acting Commissioner of Patents.

Cl. 12—67.
